(57) **CLAIM**

The ornamental design for a solar powered bug eliminator, as shown and described.

DESCRIPTION

FIG. 1 is a perspective view of the solar powered bug eliminator of the present invention;

FIG. 2 is a front elevation view; the rear elevation view being the same;

FIG. 3 is a top plan view thereof;

FIG. 4 is a left side elevation view; the right side elevation view being the same; and,

FIG. 5 is a bottom plan view.

The broken line showing of environment in the drawings is included for the purpose of illustrating only and forms no part of the claimed design.
